UNITED STATES PATENT OFFICE

HARPER A. GOOD, OF WAYNESBORO, PENNSYLVANIA, ASSIGNOR TO LANDIS TOOL COMPANY, OF WAYNESBORO, PENNSYLVANIA, A CORPORATION OF PENNSYLVANIA

MECHANISM FOR PRODUCING CURVED AXIAL SURFACE ON ROLLS

Application filed May 29, 1931. Serial No. 541,069.

This invention relates to roll grinding machines and particularly to mechanism for producing a crowned or a concave surface on the work being ground.

The object of the invention is to provide a machine of this type which will produce as nearly as possible a perfectly symmetrical curve on the surface of the work.

A further object is to provide a mechanism that is flexible and operable with any of the parts in any of the different positions to which they may be moved.

A still further object is to provide means whereby the point of contact between the grinding wheel base and an operating eccentric lies always in a straight line, and;

A still further object is to provide means whereby the movement in the straight line is always simple harmonic motion.

Further objects and advantages will become apparent as the description proceeds.

Referring to the accompanying drawings, which are made a part hereof and on which similar reference characters indicate similar parts,

Figure 1 is a rear view of mechanism for tilting the grinding wheel base,

Figure 2, a detail view of mechanism for adjusting said sub-base to central position,

Figure 3, an arrangement of the device for concaving a roll,

Figure 4, a similar view for crowning a roll,

Figure 5, a sectional front elevation of the device showing the method of driving the tilting mechanism with means for eliminating backlash,

Figure 6, a somewhat diagrammatic sketch showing the relation of the grinding mechanism to the traverse drive from the work carriage,

Figure 7, a sectional elevation on line 7-7 of Figure 1 of the jack for lifting the wheel base to set the eccentric,

Figure 8, a section on line 8-8 of Figure 7, and

Figure 9, an end elevation of the wheel base showing the tilting mechanism in its relation thereto.

In grinding a crown or concave surface

on a roll it is very necessary that these surfaces be as symmetrical as possible. The crown or concave surface moreover should be of such a form as to compensate for distortion of the roll due to pressure applied or due to changes in temperature. Since the rolls which will be ground by machines of this kind are frequently used in rolling hot steel the temperature of the roll is changed very considerably during its contact with the work being rolled, it is necessary that the crown on the roll be such as will properly compensate for changes in temperature. The mathematical sine curve seems best to fulfill the requirements for the desired crown and concavity. In order to grind such a curve on a roll two things are necessary. First, the line or point of contact between the wheel base and the lifting element must move in a straight path, and second, the movement of the said point or line must follow the rules of simple harmonic motion. The method of securing such results will now be described.

The grinding wheel 10 is mounted upon a wheel base 11 which in turn is supported on a sub-base 14. The sub-base is fulcrumed at 12 so as to tilt toward and from a work piece 13. Means for tilting this base are best shown in detail in Figures 1 and 5. The sub-base 14 of the grinding wheel has a projecting arm 15 in the form of a clamp which carries an adjusting screw 16 shown on an enlarged scale in Figure 2. The purpose of the screw is to center the wheel base after setting the crowning mechanism. The screw 16 rests on the top of a block 18. The block in turn rests on the periphery of a ball bearing assembly 19. This bearing is carried on a crank pin 20. This is the construction used in grinding a concave roll. When grinding a crown roll an extension block 21 is positioned between the end of the block 18 and the ball bearing 19. In Figure 3 the construction is shown in which a concaved roll is ground and Figure 4 shows the arrangement for grinding a crowned roll. Crank pin 20 is carried by a block 22 which is slideable in guideways 23 and 24 and is held in place by suitable gibs. The gibs also

serve to hold the crank pin in any position to which it may be adjusted. A graduated plate 25 indicates the distance of the crank pin off center and hence indicates the height 5 of the crown or the depth of the concavity. Means for driving the crank pin to tilt the wheel base will now be described.

The diagrammatic sketch given in Figure 6 shows the driving connection between a 10 motor 26 and the crown producing mechanism. The motor 26 drives a shaft 27 on the end of which is a worm 28 meshing with a worm wheel 29. The worm wheel 29 carries a shaft on the end of which is a pinion 30 15 which meshes with a pinion 31 on a shaft 32. On the shaft 32 is a bevel gear 33 meshing with a bevel gear 34 on a shaft 35. The shaft 35 has on its other end a bevel gear 36 meshing with a bevel gear 37 on a shaft 38. 20 A backlash mechanism 39 is provided intermediate the ends of the shaft 35. The end of the shaft 38 carries a pinion 40 which meshes with a pinion 41 on shaft 42. The shaft 42 has a worm 43 engaging with a 25 worm wheel 44 carried by the shaft 45 upon which the crank pin is mounted. The end of the shaft 32 also has a worm 46 meshing with a worm wheel 47 on shaft 48, the other end of the shaft 48 has a worm 49 meshing 30 with a rack 50 on the wheel carriage of the grinding machine. The operative connection just described will show that the grinding wheel is traversed past the work in proper timed relation with the operation of 35 the grinding or concaving mechanism. A backlash element 51 may be provided in the shaft 42. On the end of the shaft 42 is a bevel gear 52 which meshes with a bevel gear 53 on a shaft 54, the other end of the 40 shaft 54 carries a worm 55 which meshes with the worm wheel 44. The worm 55 is properly adjusted with relation to the position of the teeth on the worm wheel 44 to take up all backlash during reverse rotation 45 of the grinding mechanism. Gears 56, 57, 58, 59, 60 and 61 may be provided to give any desired relative variation in the speed of the shaft 54 and the speed of the shaft 42 to control the concaving and grinding 50 mechanism in response to rolls of varying length. In order to set the crowning mechanism it is necessary to lift the weight of the wheel base off the block 18. This is accomplished by means of a jack shown in detail 55 in Figure 7. A bracket 62 is secured on the carriage of the machine. Within this bracket is mounted a nut 63 which has a flange 64 which rests upon ball bearings 65. A bevel gear 66 is secured to the nut 63 as 60 by means of a pin 67. A bevel gear 68 meshes with the beveled gear 66, the beveled gear 68 being carried on the end of a shaft 69. The shaft 69 may be manually rotated by means of a wrench inserted on the 65 squared end 71 of the shaft. The head 72 of

a screw 74 seats against a pad 73 on the underside of the sub-base 14 so that the jack may be caused to support the weight of the grinding wheel base at which time the necessary adjustments for grinding or concaving a roll may be made. Keys 75 and 76 in bracket 62 prevent rotation of the screw 74. From the description given above it will be seen that each time the work carriage is traversed past the work the shaft 20 will be 75 rocked to move the grinding wheel toward and from the work in accordance with the shape of the crown or concavity desired to be formed on the work. The rate of tilting or lifting of the wheel base will be in accordance with harmonic motion since the crank pin travels in the arc of a circle and the vertical movement of the pin is that of any point in the periphery of the crank pin. Movement of the crank pin imparts linear 80 motion to the base.

In Figure 3 the dotted circle A represents the position of the crank pin when grinding a cylindrical roll in which the sub-base is 90 not tilted at all during traverse of the work carriage. Circle B in full lines shows the position of the crank pin at the center of the roll when concaving. Dotted circles C and D show the positions at the ends of the roll.

Figure 4 shows the positions of the crank pin for crowning a roll. Circle X in full lines is the central position which indicates the position at the center of the crown. Dotted circles Y and Z indicate the end positions.

It will be obvious to those skilled in the art that various changes may be made in my device without departing from the spirit of the invention and therefore I do not limit myself to what is shown in the drawings and described in the specification, but only as indicated by the appended claims.

Having thus fully described my said invention, what I claim as new and desire to secure by Letters Patent, is:

1. A roll grinding machine comprising a bed, a wheel carriage traversable upon the bed, a wheel base tiltably mounted upon the carriage and carrying a grinding wheel mounted approximately above the pivot point, a crank carrying an eccentric pin positioned adjacent the under side of the rear of the wheel base, a block positioned against said pin and the said underside of the wheel base and guided for straight line movement, and means for operating the said crank in proper timed relation with the traverse of the carriage to impart straight line movement to said block to move the said grinding wheel toward and from the said work to grind a crown or concave surface on the work said movement being in accordance with simple harmonic motion to produce approximately a mathematical sine curve on the work, substantially as set forth.

2. In a roll grinding machine having a bed and a wheel carriage traversable upon said bed, a wheel base mounted on said carriage said wheel base carrying a grinding wheel mounted thereon, means for tilting said wheel base comprising an eccentric, means for oscillating said eccentric, a block engageable with said eccentric, means for guiding said block for vertical movement, 10 said block forming operative connection between the said eccentric and the said base whereby oscillation of the eccentric will tilt the base, and means for adjusting the degree of eccentricity to produce a predetermined crown or concavity on the work as the wheel base is tilted toward and from and moved axially of the work, substantially as set forth.

3. In a roll grinding machine having a bed and means mounted thereon for supporting a roll to be ground, a wheel carriage mounted on said bed and traversable axially of the roll to be ground, a wheel base tiltably mounted upon said wheel carriage, means for tilting said wheel base toward and from the work as the wheel carriage is traversed axially of the work comprising an eccentric, means for oscillating said eccentric in timed relation with 25 movement of the wheel carriage, a block forming an operative connection between said eccentric and said tilttable base, means for guiding said block to cause it to move in a straight line and means adjustably secured in said tilttable base for forming contact between the base and the said block to provide adjustment of the tilttable base, substantially as set forth.

4. In a roll grinding machine having a bed and means mounted thereon for supporting a roll to be ground, a wheel carriage mounted on said bed and traversable axially of the roll to be ground, a wheel base tiltably mounted upon said wheel carriage, 40 means for tilting said wheel base toward and from the roll as the wheel carriage is traversed axially of the roll comprising an eccentric, means for oscillating said eccentric in timed relation with movement of the wheel carriage, a block forming an operative connection between said eccentric and said tilttable base, and means for guiding said block to cause it to move in a straight line, substantially as set forth.

5. A roll grinding machine having a bed and a wheel support, a wheel base mounted on said support having a grinding wheel mounted thereon, means for moving the wheel base comprising an eccentric, a block 55 mounted to move in a straight line engageable with said eccentric and forming the operative connection between the eccentric and the said movable base, whereby oscillation of the eccentric will move the base, substantially as set forth.

6. In a roll grinding machine having a bed, a work support and a wheel support, a wheel base mounted upon said support, means for imparting relative traversable movement between the said work support and the wheel support, said wheel support having a grinding wheel mounted thereon, means for moving said wheel support toward and from the work support, comprising an eccentric, means for oscillating said eccentric, a block mounted to move in a straight line engageable with said eccentric and forming the operative connection between the eccentric and the movable wheel support whereby oscillation of the eccentric will move the wheel support toward and from the work support, substantially as set forth.

7. In a roll grinding machine having a bed, a wheel carriage and a work support mounted on the bed and traversable one relative to the other, the wheel carriage being mounted so as to tilt toward and from the work support, means for tilting the wheel carriage comprising a crank having an eccentric pin, a block engageable with the wheel carriage and with the said pin to form the operable connection between the pin and the carriage, said block being guided for straight-line movement, and means for rotating the crank to impart such movement to the block, substantially as set forth.

8. In a roll grinding machine having a bed and a wheel carriage traversable longitudinally of the bed and a wheel base movably mounted on the said carriage, means for moving said wheel base comprising a crank carrying an eccentric pin, a block engageable with the wheel base and with the said pin to form the operable connection between the pin and the base, and means for rotating the crank to impart movement to the said block, said block being guided for straight-line movement only, substantially as set forth.

9. In a roll grinding machine having a bed and a support for a roll to be ground, a wheel carriage mounted on the bed and traversable axially of the roll to be ground, a wheel base movably mounted upon said wheel carriage, means for moving said wheel base toward and from the roll as the wheel carriage is traversed axially of the roll comprising an eccentric, means for oscillating said eccentric in timed relation with movement of the wheel carriage, a block forming the operative connection between said eccentric and said movable base, and means for guiding said block to cause it to move in a straight line, substantially as set forth.

10. In a roll grinding machine having a bed and means for supporting a roll to be ground, a wheel carriage mounted on said bed, means for imparting relative travers-

able movement between the work and the wheel carriage, a wheel base movably mounted upon said wheel carriage, means for moving said wheel base toward and 5 from the work in timed relation with the relative traverse between the wheel base and the work comprising an eccentric, means for oscillating said eccentric, a block forming the operative connection between said eccentric and said movable base, and means 10 for guiding said block to cause it to move in a straight line to impart movement to the wheel base, substantially as set forth.

In witness whereof, I have hereunto set 15 my hand at Waynesboro, Pennsylvania, this 20th day of May, A. D. nineteen hundred and thirty-one.

HARPER A. GOOD.
